UNITED STATES PATENT OFFICE.

WILLIAM CARROLL, OF EAST HAM, ENGLAND.

LIFE-BUOY.

1,205,514.

Specification of Letters Patent.

Patented Nov. 21, 1916.

Application filed June 10, 1916. Serial No. 102,924.

To all whom it may concern:

Be it known that I, WILLIAM CARROLL, residing at 68 Chester road, East Ham, Essex, England, have invented certain new and useful Improvements in Life-Buoys; and I do hereby declare the following to be a full, clear, and exact description of the invention, such as will enable others skilled in the art to which it appertains to make and use the same.

This invention relates to life buoys and has for its object to provide a life buoy of improved construction which will be lighter and of greater buoyancy than those at present in use, and which can also be more cheaply constructed.

In constructing a life-buoy according to the present invention the buoy is made of the usual annular shape and since a core 20 consisting of a single piece of wood cut to such a shape would necessarily be weak at two sections owing to the grain of the wood, an important feature of the present invention is the employment of two or more thicknesses of wood fastened to each other in the well known way with their grains arranged in different directions. By using a central core of multi-ply wood, substantially uniform strength and stiffness of every section 30 is obtained.

The accompanying drawings illustrate by way of example one construction of life-buoy in accordance with the present invention.

Figure 1 is a view in plan. Fig. 2 is a sectional view in side elevation.

In the construction illustrated I employ an annular disk *a* of four ply wood and form a covering *b* of water proof material or canvas, which is preferably made in the known manner consisting of a number of sections *b*¹, which are shaped to fit over the disk *a*. Each section *b*¹ of the covering consists of two sectors of the covering material adapted to lie one on top and the other underneath a portion of the disk *a* and attached together along their inside edges at *b*². The radial width of these sectors is greater than the width of the annular disk *a* of four ply wood. After placing the sectors *b*¹ in position they are temporarily fixed to the wood *a* by suitable clamps and the packing of buoyant material *c*, such, for instance, as kapok, is placed between the disk *a* and the cover *b*, the whole of one side being done first, the disk *a* being then turned over and

the other side being similarly packed. When the packing *c* is complete, the sections *b*¹ of the cover are temporarily sewn in position around their outside edges *b*³, 60 the upper portion of each section being attached to the lower portion of the same section. The adjacent ends *b*⁴ of the sections, of which there may be four are then inclosed by junction pieces *d* which overlap 65 the said ends *b*⁴ for a short distance. These junction pieces *d* consist of two small sectors of similar material to the cover *b* shaped to fit over the adjacent ends of the sections *b*¹ of the cover, the two small sectors being attached to each other by sewing along their inner edges *d*¹ so that one sector lies over the top of the adjacent ends of the sections *b*¹ of the cover and the other small sector is similarly disposed below. The buoy is then 70 finished off by permanently sewing together the outer edges of the whole cover including the large sections *b*¹ and the junction pieces *d*. The junction pieces *d* are also sewn to the large sections radially along their edges 75 *d*². The covering may be made of any suitable material, preferably water proof, or painted canvas may be employed.

A series of loop ropes or the like *e* are then attached to the buoy by their ends, so 85 that the loops lie outside the circumference of the buoy. Each loop *e* is provided at about its center with a cylindrical or other suitable shaped float *f* consisting of a piece of water proof material inclosing a packing 90 of kapok or other buoyant material.

It will be found that buoys according to my invention can be more cheaply constructed than those at present in use and for a given size are of greater buoyancy and less 95 weight.

What I claim and desire to secure by Letters Patent is:—

1. A life buoy comprising an annular disk of multi-ply wood, provided with a packing 100 of suitable quantity of buoyant material held in position upon said disk and inclosed by a covering of flexible or woven material.

2. A life buoy comprising an annular disk of multi-ply wood, provided on both sides 105 with a packing of suitable quantity of buoyant material held in position upon said disk and inclosed by a cover of flexible or woven material.

3. A life buoy comprising an annular disk 110 of multi-ply wood, a packing of buoyant material, a covering of flexible water-proof

material, said covering being made in sections, overlapping junction pieces covering the ends of the said sections.

4. A life buoy comprising an annular disk 5 of multi-ply wood, a packing of buoyant material, a covering of flexible water-proof material, said covering being made in sections, overlapping junction pieces covering the ends of said sections, and an exterior 10 looped flexible member attached to the buoy by being confined within said junction pieces.

5. A life buoy comprising an annular disk of multi-ply wood, and a packing of buoy- 15 ant material, a covering of flexible water-

proof material, said covering being made in sections, overlapping junction pieces covering the ends of the said sections, and an exterior looped flexible member attached to the buoy by being confined within said junction pieces, and a float upon each of said loops. 20

In testimony whereof, I have signed my name to this specification in the presence of two subscribing witnesses.

WILLIAM CARROLL.
